UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

SUPPORT FOR ROTATING STOPE-DRILLS.

1,382,325.

Specification of Letters Patent. Patented June 21, 1921.

Application filed March 22, 1920. Serial No. 367,831.

To all whom it may concern:

Be it known that I, FRED M. SLATER, a citizen of the United States, residing at Easton, in the county of Northampton and 5 State of Pennsylvania, have invented a certain new and useful Improvement in Supports for Rotating Stope-Drills, of which the following is a specification.

This invention relates to a non-rotating 10 support or foot for rock drills, more particularly rotating stope drills having a fluid operated feeding element which may be in the form of an air feed cylinder. In the type of drill selected for illustration of the 15 invention, independent means are preferably provided for rotating the drill bit.

When the drill bit sticks in operation, or 20 becomes jammed, the drill cylinder and the entire tool tend to rotate in the opposite direction to that in which the drill bit was rotating, and the primary object of the 25 present invention is to enable the entire drill to be firmly supported upon a foot piece and operated with independent rotation and air feed, but to afford means for preventing the drill cylinder from rotating.

The rock gripping foot or foot piece 30 which supports the tool is constructed in an improved manner adapted to strongly resist backward rotation of the machine, without slipping on the rock and the air feed element comprising two telescopic members in slidable but relatively non-rotatable engagement is pivotally but non-rotatably supported upon the foot piece.

The drawings illustrate a preferred form 35 of the invention in which—

Figure 1 is a side elevation partly broken away and partly in vertical section showing 40 a rock drill embodying my invention,

Fig. 2 is an enlarged detail transverse 45 sectional view on the line 2—2 of Fig. 1, and

Fig. 3 is an enlarged detail perspective 50 view of the foot piece and air feed piston rod partly broken away.

Referring to the drawings, A represents the cylinder casing of a stope drill of the percussive type, having the air feed cylinder B and any suitable or usual construction of 55 front head C, adapted to receive the rotating drill bit D. A suitable rotation motor for rotating the drill bit may be mounted on the tool, in this instance the motor casing being indicated at E. Fluid pressure is admitted to the tool at the inlet F and the

usual throttle valve is indicated at G for controlling the admission of fluid pressure to the drill cylinder and to the feed cylinder. A handle H may also be provided adapted to be grasped by the operator. The front 60 head C is held to the drill cylinder by the usual spring pressed side bolts J as shown.

The feed cylinder B telescopes over and slides upon a piston (not shown) and piston rod K, and in order to restrain the feed 65 cylinder from rotating relatively to the piston rod K, these two members have slidable but relatively non-rotatable engagement. In this instance and as a convenient construction, the piston rod K is longitudinally 70 grooved at L and the end O of the feed cylinder B is provided with longitudinal ribs or tongues P adapted to engage the grooves L and prevent the feed cylinder from turning when the piston rod K is held 75 from turning.

A non-rotating transversely extending rock engaging foot or foot piece Q is transversely pivoted or swiveled at R on the end of the piston rod K. In this instance the 80 end of the piston rod K is split or grooved at S and the body of the foot piece is inserted in the groove S and the pivot pin inserted in position. The foot piece Q is provided with rock engaging points or toes 85 T at each end which are preferably beveled to form sharp edges and these points or toes T extend rearwardly from the foot piece and outwardly at each side at opposite angles to the plane of the foot piece in directions to resist any tendency of the drill cylinder casing and feeding element to bodily 90 rotate backwardly in the reverse direction to the rotation of the drill steel. The toes T preferably point in the proper direction 95 and at the required angle to resist the tendency of the entire tool to rotate, and for this purpose the toes are forwardly inclined in the direction which the tool would tend to rotate, so that the toes dig into the rock 100 and prevent such rotation. Obviously the feed cylinder B and piston rod K may be reversed end for end as is frequently done in practice, in which case the foot piece would be attached to the outer end of the 105 cylinder B and the drill casing would be attached to the end of the piston rod.

I claim—

1. In a fluid actuated rock drill, the combination of a drill cylinder casing provided 110

with automatic rotation for the drill steel, a fluid operated feeding element comprising two telescopic members in slidable but relatively non-rotatable engagement, the drill cylinder casing being rigidly mounted on one member of the feeding element, and a non-rotating support transversely pivoted to the other member of the feeding element, said support comprising a transversely extending pivotal foot piece provided with beveled and sharpened rock engaging toes at each end extending rearwardly from the foot piece and outwardly at each side at opposite angles to the plane of the foot piece in directions to resist any tendency of the drill cylinder and feeding element to bodily rotate backwardly in the reverse direction to the rotation of the drill steel.

2. In a fluid actuated rock-drill, the combination of a drill cylinder casing provided with automatic rotation for the drill steel, a fluid operated feeding element comprising

two telescopic members in slidable but relatively non-rotatable engagement, the drill cylinder casing being rigidly mounted on one member of the feeding element, and a non-rotating support transversely pivoted to the other member of the feeding element, said support comprising a transversely extending pivotal foot piece provided with beveled and sharpened rock engaging toes at each end extending rearwardly from the foot piece and outwardly beyond the ends of the foot piece in opposite directions and also extending outwardly at each side at opposite angles to the plane of the foot piece in directions to resist any tendency of the drill cylinder and feeding element to bodily rotate backwardly in the reverse direction to the rotation of the drill steel.

In testimony whereof, I have hereunto set my hand.

FRED. M. SLATER.
